PRODUCTION OF ALKOXY-HYDROXY-BENZALDEHYDES

Ewart Mather and William Edward Hamer,
Wrexham, Wales, assignors to Monsanto
Chemicals Limited, London, England, a British
company

No Drawing. Application March 2, 1936, Serial
No. 66,698. In Great Britain March 4, 1935

10 Claims. (Cl. 260—600)

This invention consists in improvements in or relating to the production of vanillin and like alkoxy-hydroxy-benzaldehydes.

It has already been proposed to produce vanillin (3-methoxy-4-hydroxy-benzaldehyde) by the hydrolysis and oxidation, for example by means of cupric acetate, of trichloromethylguaiacylcarbinol. It has also been proposed to produce 3-ethoxy-4-hydroxy-benzaldehyde (which is commonly known as ethylvanillin but which is referred to hereinafter by the trade-marked name "Ethavan") by subjecting trichloromethylguaiacylcarbinol in one and the same solution simultaneously or in succession to hydrolysis and oxidation by means of a reducible heavy metal compound. Other suggestions for the same or similar processes include the use of salts of alkaline reaction, containing a non-volatile anion, as condensing agents, and in other cases the use 20 of air, or oxygen, or of nitro-aryl sulphonic or carboxylic acids as oxidizing agents. In such processes it is thought that the trichlorocarbinol compound (produced for example by the condensation of chloral or choral hydrate with a 2-alkoxy phenol) is hydrolyzed to the corresponding hydroxy acid which is then converted to the corresponding benzaldehyde by oxidation, carbon dioxide being eliminated.

As an alternative process it has been proposed 30 to condense pyrocatecholmonoalkylether with glyoxylic acid, and to oxidize the condensation product with compounds of heavy metals or with aromatic nitro bodies; no specific example of the aromatic nitro bodies to be employed has, however, been given.

It is an object of the present invention to provide a process whereby vanillin and like alkoxy-hydroxy-benzaldehydes may be obtained in good yields on a large scale.

According to the present invention a process 40 for the production of vanillin and like alkoxy-hydroxy-benzaldehydes comprises oxidizing a compound having the general formula:

(where R represents an alkyl group) to the corresponding 4-hydroxy-3-alkoxy-benzaldehyde by

heating (for example at temperatures above 110° C. and below 170° C.) in an aqueous solution of caustic alkali with an aryl nitro compound in which the aryl group does not contain any negative substituent.

The present invention is not restricted to any particular method for the preparation of the hydroxy acid, but preferably in carrying out the present invention the hydroxy acid is obtained by hydrolyzing the trichlorocarbinol compound produced by the condensation of chloral or chloral hydrate with a 2-alkoxy phenol. The hydrolysis by the aqueous alkali and the oxidation of the hydroxy acid (and of related compounds which may possibly be formed at the same time) may 15 be effected either successively or simultaneously.

The preferred aryl nitro compound for use in accordance with the present invention is nitrobenzene which is readily available at a relatively low price. Other compounds which may 20 be employed are, for example, nitrotoluene, di-nitrobenzene and their homologues. Although fairly good yields are obtained with nitrobenzene on heating at temperatures of 110° C., it is found that a temperature of about 150° C. is most convenient when speed of operation is considered as 25 well as yield of product. In carrying out the invention in order to obtain the necessary temperatures, in most cases, it will be necessary to effect the oxidation in an autoclave. During the 30 course of the reaction it is found that the mono-nitro compounds are converted mainly to azoxy compounds, which may be recovered as valuable by-products.

A number of specific examples are given below 35 by way of example only in order to illustrate the process of the present invention.

Example I

54.3 grms. of trichloromethylguaiacyl carbinol 40 were dissolved in a solution of 75 grms. of commercial caustic soda of 97 to 98% sodium hydroxide content in 660 ml. water, and 25 grms. of nitrobenzene were added. This charge was then heated for two hours at 150° C. in a steel 45 autoclave. After cooling, nitrobenzene and its reduction products were removed by extracting the oxidized charge with benzene. The extracted alkaline solution was then acidified with hydrochloric acid and the crude vanillin was extracted 50 with ether, when, after removal of this solvent, 31.37 grms. of crude vanillin were obtained. On vacuum distillation, this crude vanillin gave 83.6% of its weight of distilled vanillin of melting point 72-77° C., i.e., a yield of pure vanillin equal 55

to about 80% of that theoretically obtainable from the carbinol.

Example II

- 5 54.3 grms. of trichloromethylguaiacyl carbinol were dissolved in a solution of 120 grms. of commercial caustic potash of 87 to 88% potassium hydroxide content in 660 ml. of water, and 25 grms. of nitrobenzene were added. This charge 10 was then heated for 2 hours at 150° C. in a steel autoclave. After cooling, nitrobenzene and its reduction products were removed by extracting the oxidized charge with benzene. The extracted alkaline solution was then acidified with hydrochloric acid and the crude vanillin was extracted with ether, when, after removal of this solvent, 30.98 grms. of crude vanillin were obtained. On vacuum distillation this gave 85.4% of its weight of distilled vanillin of melting point 15 73-78° C., i. e., a yield of pure vanillin equal to about 80% of that theoretically obtainable from the carbinol.

Example III

- 25 54.3 grms. of trichloromethylguaiacyl carbinol were dissolved in a solution of 75 grms. of commercial caustic soda of 97 to 98% sodium hydroxide content in 660 ml. water, and 20 grms. of meta-dinitrobenzene were added. This charge 30 was then heated for 2 hours at 150° C. in a steel autoclave. After cooling meta-dinitrobenzene and its reduction products were removed by extracting the oxidized charge with ether. The extracted alkaline solution was then acidified with hydrochloric acid and the crude vanillin was extracted with ether, when, after removal of this solvent, 30.64 grms. of crude vanillin were obtained. On vacuum distillation, this crude vanillin gave 89.7% of its weight of distilled vanillin of melting point 35 73.5-78° C., i. e., a yield of pure vanillin equal to about 80% of that theoretically obtainable from the carbinol.

When a copper lined autoclave was used instead of the steel autoclave, a very similar yield of vanillin was obtained.

45

Example IV

- 50 57.1 grms. of trichloromethylguaiethyl carbinol were dissolved in a solution of 75 grms. of commercial caustic soda of 97 to 98% sodium hydroxide content in 660 ml. of water and 25 grms. of nitrobenzene were added. This charge was then heated for 8 hours at 110° C. in a steel autoclave. After cooling, nitrobenzene and its reduction products were removed by extraction 55 with benzene. The extracted alkaline solution was acidified with hydrochloric acid and the crude Ethavan (3-ethoxy-4-hydroxybenzaldehyde) extracted with ether. The ether solution was washed with sodium bicarbonate solution, dried over sodium sulphate, and the solvent removed by distillation. 14.75 grms. of Ethavan of melting point 60 67.5-71.0° C. were obtained, i. e., a yield of pure Ethavan equal to about 40% of that theoretically obtainable from the carbinol.

65

Example V

- 70 57.1 grms. of trichloromethylguaiethyl carbinol were dissolved in a solution of 75 grms. of commercial caustic soda of 97 to 98% sodium hydroxide content in 660 ml. of water, and 25 grms. of nitrobenzene were added. This charge was then heated for two hours at 150° C. in a steel autoclave. After cooling, nitrobenzene and its reduction products were removed by extraction 75 with benzene. The extracted alkaline solution

was acidified with hydrochloric acid and the crude Ethavan (3-ethoxy-4-hydroxybenzaldehyde) extracted with ether. The ether solution was washed with sodium bicarbonate solution, dried over sodium sulphate, and the solvent removed by distillation. 28.15 grms. of Ethavan of melting point 66.0-71.5° C. were obtained, i. e., a yield of pure Ethavan equal to about 80% of that theoretically obtainable from the carbinol.

Example VI

- 5 57.1 grms. of trichloromethylguaiethyl carbinol were dissolved in a solution of 75 grms. of commercial caustic soda of 97 to 98% sodium hydroxide content in 660 ml. of water, and 25 grms. of nitrobenzene were added. This charge was then heated for 1 hour at 170° C. in a steel autoclave. After cooling, nitrobenzene and its reduction products were removed by extraction with benzene. The extracted alkaline solution was acidified with hydrochloric acid, and the crude Ethavan (3-ethoxy-4-hydroxybenzaldehyde) extracted with ether. The ether solution was washed with sodium bicarbonate solution, dried over sodium sulphate, and the solvent removed by distillation. 30.62 grms. of Ethavan with the rather low melting point of 60-69° C. were obtained.

Example VII

- 10 57.1 grms. of trichloromethylguaiethyl carbinol were dissolved in a solution of 75 grms. of commercial caustic soda of 97 to 98% sodium hydroxide content in 660 ml. of water, and 25 grms. of commercial meta-nitrotoluene were added. This charge was then heated for 2 hours at 150° C. in a steel autoclave. After cooling, nitrotoluene and its reduction products were removed by extraction with benzene. The extracted alkaline solution was acidified with hydrochloric acid, and the crude Ethavan (3-ethoxy-4-hydroxybenzaldehyde) extracted with ether. The ether solution was washed with sodium bicarbonate solution, dried over sodium sulphate, and the solvent removed by distillation. 27.05 grms. of Ethavan of melting point 25 68.5-71.0° C. were obtained, i. e., a yield of pure Ethavan equal to about 80% of that theoretically obtainable from the carbinol.

Example VIII

- 30 50 150 grms. of trichloromethylguaiethyl carbinol were dissolved in a solution of 150 grms. of commercial caustic soda of 97 to 98% purity in 1000 ml. of water. The mixture was cautiously heated to boiling and then boiled for 15 mins. at atmospheric pressure, cooled to room temperature, and acidified with 400 ml. of approximately 10-N hydrochloric acid. A sticky resin which formed was filtered off and discarded, and the aqueous filtrate extracted with ether. The ether extract was then shaken with a solution of 50 grms. of sodium bicarbonate in 500 ml. water. The ether layer was discarded and the bicarbonate extract treated with 15 ml. of approximately 10-N hydrochloric acid, and then extracted successively with two portions of ether of 250 ml. each, and then with a further 100 ml. portion. The ether extract was evaporated down, and left a small amount of resinous material, which was discarded. The bicarbonate extract was then treated with an excess of hydrochloric acid and extracted with two successive portions of 250 ml. each of ether. This ether extract yielded, on evaporation, 40.4 grms. of crude guaethyl glycolic acid. This solid was purified by recrystallisa- 35 40 45 50 55 60 65 70 75 80 85 90 95 100

75

tion from ethylene dichloride, and it then melted at about 126° C. and had an equivalent, determined by titration, of about 213.

26.5 grms. of the recrystallised guaethyl glycollic acid melting at about 126° C., were dissolved in a solution of 31.25 grms. of commercial 5 97 to 98% caustic soda in 412.5 ml. of water. 24 grms. of nitrobenzene were added and the mixture heated in a steel autoclave for 2 hours at 10 150-154° C. The mass was then cooled, the excess nitrobenzene and the reduction products of nitrobenzene removed by extraction with benzene, and the alkaline aqueous layer acidified with hydrochloric acid and extracted with ether. 15 On evaporation, the ether solution yielded 21.15 grms. of crude 3-ethoxy-4-hydroxy-benzaldehyde. This crude product, on vacuum distillation, yielded 91.75% of its weight of 3-ethoxy-4- 20 hydroxybenzaldehyde of melting point 69-71° C., i. e., a yield of the pure product equivalent to about 85% of that theoretically obtainable from the glycollic acid used.

We claim:

1. A process for the production of alkoxy-hydroxy-benzaldehydes comprising heating a compound having the general formula:

35 in which R is an alkyl group and X is a group selected from the class consisting of trichloromethyl ($-CCl_3$) and carboxyl ($-COOH$) groups, in an aqueous solution of caustic alkali with an aryl nitro compound that is free of any negative 40 substituent.

2. A process for the production of alkoxy-hydroxy-benzaldehydes comprising simultaneously hydrolyzing and oxidizing a 4-hydroxy phenyl-3-alkoxy trichlorocarbinol compound to the corresponding 4-hydroxy-3 - alkoxy - benzaldehyde by heating in an aqueous solution of caustic alkali with an aryl nitro compound that is free of any negative 45 substituent.

3. The process of claim 1 wherein the heating is conducted at a temperature between 110° and 170° C.

4. The process of claim 2 wherein the heating is conducted at a temperature between 110° and 170° C. 5

5. The process of claim 1 wherein the aryl nitro compound is a compound selected from the group consisting of nitrobenzene, meta-dinitrobenzene and meta-nitrotoluene. 10

6. The process of claim 2 wherein the aryl nitro compound is a compound selected from the group consisting of nitrobenzene, meta-dinitrobenzene and meta-nitrotoluene. 15

7. A process for the production of alkoxy-hydroxy-benzaldehydes comprising condensing a compound selected from the group consisting of chloral and chloral hydrate with a 2-alkoxy phenol and hydrolyzing and oxidizing the trichlorocarbinol compound produced to form the corresponding 3-alkoxy-4-hydroxy benzaldehyde, the oxidation being effected by heating in an aqueous solution of caustic alkali with an aryl nitro compound in which the aryl group is free of any negative substituent. 20

8. A process for the production of 3-methoxy-4-hydroxy-benzaldehyde comprising hydrolyzing trichloromethylguaiacyl carbinol and then oxidizing the hydrolysis product by heating at a temperature between 110° and 170° C. in an 30 aqueous solution of caustic alkali with an aryl nitro compound selected from the group consisting of nitrobenzene, meta-dinitrobenzene and meta-nitrotoluene. 35

9. The process of claim 8 wherein the hydrolysis and oxidation are carried out simultaneously.

10. A process for the production of 3-ethoxy-4-hydroxy-benzaldehyde comprising hydrolyzing trichloromethylguaiacyl carbinol and then oxidizing the hydrolysis product by heating at a 40 temperature between 110° and 170° C. in an aqueous solution of caustic alkali with an aryl nitro compound selected from the group consisting of nitrobenzene, meta-dinitrobenzene and meta-nitrotoluene. 45
